(57) **CLAIM**

The ornamental design for a head-neck posture support, as shown and described.

DESCRIPTION

FIG. 1 is a perspective view of the head-neck posture support of the instant invention;

FIG. 2 is a top view thereof;

FIG. 3 is a bottom view thereof;

FIG. 4 is a left side view thereof;

FIG. 5 is a right side view thereof;

FIG. 6 is a lower end view thereof; and,

FIG. 7 is an upper end view thereof.

1 Claim, 5 Drawing Sheets**FIG. 1**

FIG. 2

FIG. 3

FIG. 4

FIG. 5

FIG. 6

FIG. 7
